UNITED STATES PATENT OFFICE

PAUL H. TODD, OF KALAMAZOO, MICHIGAN

SOAP

No Drawing. Original application filed May 25, 1927, Serial No. 194,234. Divided and this application filed August 2, 1929. Serial No. 383,165.

This invention relates to germicidal soap.

This application is a division of my application for Letters Patent filed May 25, 1927, Serial No. 194,234.

5 The object of this invention is to provide an improvement in germicidal soaps, particularly in mercuric germicidal soaps. It is a particular object to increase the germicidal quality and modify the harshness of such 10 soap.

Heretofore, an effective germicidal soap has been prepared by incorporating about two percent of a mercuric salt, for example mercuric chloride, in a good ordinary toilet 15 soap base. Such a soap, though strongly germicidal, is harsh in its effect upon the skin owing to the corrosive action of the combined mercury.

I have found that by using such a mercuric 20 salt in conjunction with cresol in soap, it is possible to obtain a soap with a high degree of efficiency as a germicide, but with a considerably milder action upon the skin, this latter quality being evidently due to the 25 greater effectiveness of mercuric salts when used in conjunction with cresol, making it possible to use a considerably smaller percentage of the mercuric salt and still obtain a soap with a high germicidal efficiency.

30 There is what might be called a synergistic 75 relation between the germicidal actions of soluble mercuric salts and cresol.

I have found, for example, that a good ordinary soap base made from cocoanut and 35 olive oils, in the proportion of one part by weight of olive oil to five of cocoanut oil, properly saponified with caustic soda, and impregnated with one percent of mercuric chloride and ten percent of cresol kills 40 *Staphylococcus aureus* and *Bacillus coli* within five minutes at 20° C. in an eight percent solution; that is, when the organisms are immersed for five minutes in a solution of eight grams of the soap in ninety-two grams 45 of water.

In preparing my soap, I have as an example taken by weight 500 parts of Cochin cocoanut oil and 100 parts of olive oil and saponified the mixed oils with 107 parts of 50 caustic soda dissolved in 214 parts of dis-

tilled water, stirring the alkali into the oils and crutting until saponification was well under way. I then heat the mixture until the saponification is complete. I then crutch 55 10.3 parts of mercuric chloride dissolved in 30 parts of boiling water, into the soap, together with 103 parts of cresol, U. S. P. After thorough crutting, the hot soap is poured into a small soap frame, where it is cooled and cut up ready for use.

60 The improved soap can be prepared by taking a good quality of toilet soap like the well known "Ivory" and milling or crutting my special ingredients into it.

Having thus described my invention, what 65 I claim as new and desire to secure by Letters Patent, is:

A soap composition containing cresol 1% to 15% and mercuric chloride $\frac{1}{4}\%$ to 3%.

In witness whereof I have hereunto set my 70 hand.

PAUL H. TODD.
